[57] **ABSTRACT**

A method of using a material having no significant toxicity as a simulant to challenge the V and G toxic agent alarm to insure alarm sensitivity and function.

4 Claims, No Drawings

TESTING A TOXIC AGENT ALARM WITH A NONTOXIC SIMULANT

DEDICATORY CLAUSE

The invention described herein may be manufactured, used, and licensed by or for the Government for governmental purposes without the payment to us of any royalty thereon.

Our invention relates to a method of using a material having no significant toxicity as a simulant to challenge the V and G toxic agent alarm, such as disclosed in U.S. Pat. application Ser. No. 768,560 filed on Oct. 16, 1968, to insure the sensitivity and function of the alarm.

Due to the dissemination of toxic compounds such as hydrogen cyanide, hydrogen sulfide, and chemical warfare agents in the atmosphere in industrial plants having hazardous atmospheres and in warfare, techniques and apparatus were necessary to monitor the existence of low concentration, such as 0.2×10^{-6} to 0.4×10^{-6} grams of contaminant toxic compound per liter of air, hazardous air contaminants. To satisfy the need for the above mentioned technique and apparatus, the device as disclosed in the aforementioned U.S. Pat. application Ser. No. 768,560 was conceived and reduced to practice. Upon conception and reduction to practice of the device disclosed in the aforementioned patent application, the problem arose as to how to insure reliability of function and sensitivity of the device by using a material having no significant toxicity as a simulant and which would nevertheless mimic the toxic V and G agents, such as disclosed in U.S. Pat. Nos. 2,926,072 and 2,929,791, and challenge the alarm. Our invention was conceived and reduced to practice to satisfy the need for a material having no significant toxicity to

function as the aforementioned simulant and to solve the aforementioned simulant problem.

A principal object of our invention is to provide a method whereby a toxic V and G agent alarm can be challenged by a material which has no significant toxicity but which mimics the V and G agents to insure reliability of function and sensitivity of the alarm.

Other objects of our invention will be obvious from the specification hereinafter set forth.

Our invention will now be described in detail as follows.

The electrochemical cell and methodology, as disclosed in foregoing U.S. Pat. application Ser. No. 768,560, has been standardized as a method and means to monitor the presence of V and G agents. The electrochemical method and means is based on the capability of a silver electrode to detect submicrogram quantities of the cyanide ion. G agents absorbed into the cell electrolyte are detected through a direct reaction with an oxime which results in the rapid formation of cyanide ions which diffuse throughout the electrolyte and are detected by the silver electrode. V agents are not detected directly by the oxime reaction, but they are converted to their corresponding G analogues by means of chemical reaction with an impregnate in a conversion prefilter. G agents react with an oxime; such as isonitrosobenzoyl acetone, to liberate the cyanide ion and produce the $\text{Ag}^+ + 2\text{CN}^- \rightarrow \text{Ag}(\text{CN})_2^-$ electrochemical reaction at the silver electrode. Each decade change in cyanide ion concentration in the alarm cell electrolyte produces a 120MW change in potential which enables G and V agent detection and quantitative estimation. G agent analogues are detected in the same manner as described for the G agent. The mechanics of the oxime reaction are as follows.

1. Formation of the oxime anion

2. o-phosphorylation of the oxime anion

3. Rapid cleavage of the oxime phosphonate

Silver nitrate and potassium fluoride are impregnated in the conversion filter to convert V agent to G analogues, such as phosphonofluorides, to react with the oxime; G agent not being reactable with the chemical composition of the conversion filter. While not a part of this invention, the process of impregnating the conversion filter is as follows.

The impregnation solution must be made immediately prior to use and cannot be stored, and the solution should be mixed and used only in polyethylene or polypropylene vessels. 187.5 ± 0.2 g of silver nitrate are dissolved in 400 ± 5 ml of deionized or distilled water, and 125.0 ± 0.1 g of potassium fluoride are dissolved in a separate container in 440 ± 5 ml of deionized or distilled water. While stirring the potassium fluoride solution, slowly add the solution of silver nitrate. The resulting mixture of the two solutions will contain a turbid, tan suspended precipitate which is then filtered using a single sheet of Whatman No. 42 filter paper. The filtrate is retained and the precipitate discarded. While stirring the filtrate, 125 ± 5 ml of absolute ethyl alcohol are added. A muddy, brown precipitate forms in suspension and should not be filtered out, because the precipitate will disappear and the liquid will clear as the below referenced dewaterproofed paper is impregnated. Pour approximately 965 ml of the impregnating liquid into a $7\frac{1}{2}$ by 12 inch polyethylene tray. Impregnate one sheet of dewaterproofed type 5 paper at a time by completely immersing the sheet, removing all trapped air bubbles, and soaking the paper for 25 to 30 seconds. Remove the paper from the impregnating solution and drain excess liquid back into the tray. White or gray spots on the paper indicate incomplete dewaterproofing or contamination, and paper with this indication should be discarded. Sheets of impregnated paper are placed on polyethylene-covered glass plates and dried, in a preheated oven at $120^\circ \pm 5^\circ\text{F}$ for 11 ± 1 hour. Impregnated paper should be placed in the oven within five minutes after impregnation. After drying, the sheets are removed from the oven, cut into a size and shape suitable for a given application, and stored immediately in opaque polyethylene containers at a relative humidity of less than 35 percent. Processed filters are not to be stored over or with silica gel or at relative humidities above 35 percent to avoid degradation of conversion efficiency.

In order to solve the above referenced simulant problem, it was necessary to conduct a research program to develop a material which mimicked V agent in terms of chemical reaction with the conversion filter impregnate and chemical reaction with the oxime and nevertheless possessed no significant toxicity. The toxicity of the V agent is ascribed to two factors; namely, a high affinity for the enzyme cholinesterase and an easy release of the leaving group in the V molecule. High affinity for the enzyme cholinesterase is due to the presence of a tertiary amine which at physiological pH is protonated; whereas the easy release of the leaving group is correlated with the basicity of the leaving ion, increase of the acidity of the anion resulting in more rapid departure. In view of the foregoing toxicity factors, research effort for a material to solve the aforementioned simulant problem was directed along lines to delete the portion of the molecule responsible for the affinity for the enzyme while at the same time increasing the basicity of the leaving group and not significantly altering the basic structure responsible for chemical reactivity.

During the course of research, it was unexpectedly found that the above simulant problem was solved by chemical compounds having the generic structure

- 10 Wherein R is any alkyl group having C₁ to C₁₂ inclusive. The preferred compound of our invention is O,S diethyl methylthiophosphonate which has a boiling point of 44°C at 0.3 mm, has a saturation vapor content of approximately 1.5mg/liter at 25°C , has an activity toward bovine erythrocyte cholinesterase of approximately 1/10000 that of the V agent activity, produces a reproducible, immediate, and excellent response in the agent alarm to a concentration of $0.4\mu\text{g}$ of simulant per liter of air. Our inventive simulant is prepared by 15 the methodology as follows.

- 25 30 35 40 45 50 55 60 65
1. Distilled diethylmethyl phosphonite at $120^\circ\text{--}121^\circ/760$ mm

To 32.4 g (0.24 mole) diethylmethyl phosphonite at 3°C was added a mixture of 4.0 ml H_2O and 0.3 ml of HCl (4.3 g $\text{H}_2\text{O} = 0.24$ mole H_2O). No reaction occurred until the heterogeneous mixture was allowed to warm up to ca. 25°C . Temperature went up to ca. 75°C and mixture cleared up to a homogenous waterwhite liquid which was distilled. First fraction distilled at $32^\circ\text{--}37^\circ/35$ mm (probably starting material); second fraction distilled at $88^\circ\text{--}92^\circ\text{C}/35$ mm lit bp = $70^\circ\text{--}15^\circ\text{C}$; K. A. Petrov, et al., Zhurnal Obschchei Khimii, 31, 179 (1961). Yield of second fraction = 20.4 g.

2. C. Borecki, et al., J. Chem. Soc., 4081 (1958)

Ethyl methylphosphinate (20.4 g, 0.19 mole) was added to a solution of 40 g (0.17 mole) sodium in ca 125 ml ethanol with no apparent reaction. To the clear solution, half gram portions of sulfur were added, allowing the added sulfur to dissolve before any more was added. The temperature was kept between 10° and 17° with an ice bath. After 5.1 g sulfur was added, no more sulfur dissolved. The mixture was allowed to warm to room temperature with stirring. After standing overnight at room temperature, a small amount of sulfur (0.5 g) was filtered off; the total amount of sulfur used was 4.6 g (0.14 mole). The filtrate was evaporated to dryness in vacuo to leave a white hygroscopic solid; it was ground under ether, dried in a desiccator and bottled under anhydrous conditions using a glove-bag. The best sample had a mp = $200^\circ\text{--}205^\circ\text{C}$ (decomposition with evolution of a gas).

3. To a solution of 19.4 g (0.12 mole) of O-ethyl-S-sodio methylthiophosphonate in ca 450 ml acetonitrile was added 21.5 g (0.2 moles) ethyl bromide. There was no apparent reaction. The solution was refluxed 6 hrs. The solvent was stripped off in vacuo and the residue distilled at 44°/0.3 mm to give 16.7 g O,S-diethyl methylthiophosphonate.

It is obvious that other modifications can be made of our invention, and our invention is to be limited only by the scope of the appended claims.

We claim:

1. A method of testing or challenging an alarm for the detection of toxic G and V agents by using a simulant compound which has no significant toxicity, said alarm including an electrochemical cell with a silver electrode for the detection of CN^- ions, said cell having an electrolyte including an oxime for reaction with phosphonofluoridates or G agents or analogs, whereby CN^- ions are generated, said alarm further including AgNO_3 and KF for the conversion of V agents to G analogs, comprising the steps of providing an air sample containing said simulant compound having the formula

- 5 wherein R is any C_1 through C_{12} alkyl group, reacting said compound of the air sample with the AgNO_3 and KF to produce the corresponding fluoridate, passing said fluoridate to the electrochemical cell and reacting said fluoridate with the oxime in the electrolyte of the 10 electrochemical cell of the alarm to produce CN^- ions in the cell electrolyte, reacting the CN^- ions at the silver electrode of the electrochemical cell to produce a change in potential, and monitoring the change in potential to determine the alarm challenge.
- 15 2. The method of claim 1 wherein R is C_2H_5 .
3. The method of claim 2 wherein the simulant compound has a boiling point of 44°C at 0.3 mm and a saturation vapor content of approximately 1.5 mg/liter at 20 25°C.
4. The method of claim 1 wherein the simulant compound concentration is 0.4 g/liter of air.
